UNITED STATES PATENT OFFICE.

HENRY P. RESTON, OF OAKLEY, OHIO, ASSIGNOR TO THE CINCINNATI PLANER COMPANY, OF OAKLEY, OHIO, A CORPORATION OF OHIO.

SAFETY RATCHET-LEVER.

1,018,080.

Specification of Letters Patent. Patented Feb. 20, 1912.

Application filed September 16, 1911. Serial No. 649,649.

To all whom it may concern:

Be it known that I, HENRY P. RESTON, a citizen of England, residing at Oakley, Ohio, have invented a new and useful Improvement in Safety Ratchet-Levers, of which the following is a specification.

My invention relates to safety ratchet levers of the class adapted to rotatively adjust the rail feed screws of metal planers or for other suitable purposes, and the objects of my improvements are to provide means for automatically moving and maintaining under a yielding pressure the detent or pawl out of engagement with the ratchet wheel; to provide means for positively locking the mechanism out of engagement; to provide reversible means for the device; to provide means for engaging the pawl with the ratchet wheel under a yielding pressure, and to provide simple and durable construction and assemblage of the various parts for securing facility of operation, safety and efficiency of action. These objects may be attained in the following described manner as illustrated in the accompanying drawings, in which:

Figure 1 is a front elevation with parts in section of a safety ratchet lever embodying my improvements; Fig. 2 a longitudinal section; Fig. 3 a perspective view of the latch lever, and Fig. 4 a section on the line *a—a* of Fig. 1.

In the drawings, 1 represents a shaft or screw journaled in the usual bearings, 2 a ratchet wheel splined thereon and formed with oppositely extended hubs, 3 and 4, and with peripheral teeth 5 which are preferably rectangular in cross-section. A cylindrical housing 6 is formed with a bore 7 wherein hub 3 is journaled and with a counter-bore 8 wherein the toothed portion of the wheel 2 may turn freely.

A keeper 9 mounted to turn on hub 4 and secured to the housing by means of screws 11 serves to retain the ratchet wheel in proper position therein. A radial arm 12 integral with the housing is formed with an axial opening 13 therethrough which is counter-bored to form annular shoulders or offsets 14, 15 and 16 therein. Said arm is also formed with a transverse opening 17 adjacent to the shoulder 15 for the movement therein of the latch lever 18 which is pivotally secured to lugs 19 formed of one side of the arm 12. A plunger 21 slidably

mounted within the axial opening of the arm 12 is reduced in size in its upper portion to form an annular shoulder 22 and increased in size at its opposite end to form a boss 23 which is adapted to contact with shoulder 16. Said boss is formed with longitudinal grooves 24 and counter sinks 25 alternately disposed quartering in its face for automatically engaging with the spring actuated locking pin 26 which is mounted in an opening 27 formed in the housing as shown in Fig. 4. A wide nose 28 formed with a taper on one side projects from the end of boss 23 for engaging with its face the teeth of the ratchet wheel and for preventing its opposite or slanting side from engaging therewith.

A sleeve 31 slidably mounted on the plunger may be actuated in one direction thereon by means of the bell crank lever 18 for compressing the coiled spring 32 which encircles the plunger between shoulder 22 thereon and said sleeve. A milled head 33 secured on the end of the plunger serves to adjust it rotatively and also to compress the coiled spring 34 which encircles the plunger thereunder and in contact with the shoulder 14. Said spring 34 serves to move and maintain the plunger under a yielding pressure in its normal position with the nose 28 out of engagement with the ratchet wheel. A quarter turn of the plunger by means of the head 33 serves to automatically engage the locking pin 27 with the corresponding counter sink 25 to positively lock the plunger in its disengaged position with nose 28 in the plane of rotation of the ratchet wheel as an additional preventative to its accidental engagement with the teeth thereof.

In operation, the plunger may be turned in either of opposite directions by means of the milled head thereon for disengaging the locking pin from the counter sink and slidably engaging it with the corresponding groove in the boss. The bell crank lever 100 may now be actuated with the sleeve on the plunger to compress spring 32 for overcoming the exertion of spring 34 in the opposite direction whereby the nose engages with the ratchet wheel and serves to rotatively adjust it with the shaft as desired. Upon releasing the latch lever, the exertion of spring 34 moves and maintains the plunger with the pawl out of engagement with the ratchet wheel. A quarter turn of the plunger in 110

this position causes the locking pin to automatically engage with the corresponding counter sink as an additional protection to any accidental movement of the plunger with 5 the nose thereon into reengagement. The width of the pawl being greater than the width of the space between the ratchet teeth also serves to prevent its engagement while turned in the plane of the rotation of the 10 wheel.

This device is especially adapted to rotate a feed screw in either direction for effecting a micrometer adjustment of the tool head on the rail of a metal planer where the 15 swing of the lever is limited and where its accidental engagement must be prevented during the power driven action of the screw.

Having fully described my improvements what I claim as my invention and desire to 20 secure by Letters Patent of the United States is:

1. The combination of a tubular member, a plunger therein formed with a latch, a spring for moving and maintaining the plunger longitudinally in one direction, and a hand actuated spring for overcoming the exertion of the former spring and for moving and maintaining the plunger under a yielding pressure in the opposite direction. 25

2. The combination of a rotative shaft, a ratchet wheel splined thereon, a lever mounted to turn on the wheel, a plunger movable longitudinally within the lever and formed with a flat tapering nose adapted to engage 30 with the wheel, a spring for moving and maintaining the plunger with the nose out of engagement with the wheel, and hand actuated spring mechanism constructed and arranged to overcome the exertion of said 35 spring and for moving and maintaining under a yielding pressure the plunger in the opposite direction with the nose in engagement with the wheel.

3. The combination of a ratchet wheel, a

lever mounted to turn thereon, a rotatively adjustable plunger movable longitudinally within the lever and formed with a slanting nose adapted to engage with the wheel, said plunger being also formed with a longitudinal groove and a counter sink in its face, and a spring actuated locking pin adapted to automatically engage with the groove and counter sink successively for maintaining the plunger under a yielding pressure in predetermined positions of rotative adjustment.

4. The combination of a ratchet wheel, a lever movable in relation thereto, a detent movable with the lever, a spring for maintaining the detent under a yielding pressure out of engagement with the wheel and a hand controlled spring for overcoming the exertion of the former spring and for moving and maintaining the detent under a yielding pressure into engagement with the wheel.

5. The combination of a ratchet wheel, a lever movable parallel to the plane thereof, a spring controlled reversible detent adapted to be engaged with the wheel under a yielding pressure and movable with the lever, and automatic means for locking the detent out of engagement with the wheel.

6. In a safety ratchet lever the combination of a ratchet wheel, a radial arm movable in relation thereto, a longitudinally movable pawl carried by the arm and adapted to detachably engage with the wheel, oppositely disposed springs for moving and maintaining the pawl in respective opposite directions under a yielding pressure, and lever connections for increasing the exertion of one of said springs for overcoming the exertion of the other said spring.

HENRY P. RESTON.
